(57) **CLAIM**

The ornamental design of a vehicle top advertisement display, as shown and described.

DESCRIPTION

FIG. 1 is a top perspective view of a vehicle top advertisement display;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a bottom perspective view thereof.

The broken lines showing advertisement graphics in FIGS. 1-3 and 8 are included for the purpose of illustrating environmental structure and forms no part of the claimed design.

1 Claim, 8 Drawing Sheets
